G. W. GRANT.
MOTH AND VERMIN PROOF GARMENT HANGER.
APPLICATION FILED JULY 19, 1918.

1,295,480.

Patented Feb. 25, 1919.

Inventor
George W. Grant

By *J. W. Bryant* Attorney.

UNITED STATES PATENT OFFICE.

GEORGE W. GRANT, OF LOCKPORT, NEW YORK.

MOTH AND VERMIN PROOF GARMENT-HANGER.

1,295,480.

Specification of Letters Patent. Patented Feb. 25, 1919.

Application filed July 19, 1918. Serial No. 245,718.

To all whom it may concern:

Be it known that I, GEORGE W. GRANT, a citizen of the United States, residing at Lockport, in the county of Niagara and 5 State of New York, have invented certain new and useful Improvements in Moth and Vermin Proof Garment-Hangers, of which the following is a specification.

The primary object of the invention is the 10 provision of a combination hanger for jackets, waists, skirts, coats, trousers, and other pieces of wearing apparel, the device being exceedingly simple in construction and easy and inexpensive to manufacture.

15 A further object of the invention is the provision of a garment hanger formed by stamping from sheet material and designed without the employment of any extraneous devices to grip and hold the articles of wearing apparel in properly suspended positions.

20 A still further object of the invention is the provision of laminations in the sheet material from which the device is formed, some of which are anti-moth or vermin proof layers which contact all articles hung upon the device.

My hanger having insecticide properties and flat-form is readily packed with clothing in a suitcase or trunk ready for instant use when required and preventing the operation of moths in the meantime.

With these general objects in view and others that will appear after the nature of the invention is better understood, the same consists in the arrangement of parts herein-after fully described in connection with the accompanying drawing, in which like reference characters designate corresponding parts throughout the several views.

25 In the said drawing:

Figure 1 is a perspective view of the device with a pair of trousers indicated by dotted lines operatively suspended therefrom;

Fig. 2 is a side view thereof illustrating the operation of securing a garment therein; and

Fig. 3 is a central transverse sectional view thereof.

50 Referring more in detail to the drawing, the simplicity and economical features of the device will be at once apparent as the complete hanger consists of a comparatively thin laminated plate 10 formed in a single

piece by stripping or cutting the same out of 55 suitable sheet material of a flexible nature.

The device is substantially triangular in configuration having its oppositely inclined sides 11 adapted to sustain the weight of a coat, jacket or other garment properly distributed throughout the length of the device, while a centrally positioned neck 12 projects 60 upwardly for holding a garment collar in shape and is provided with a perforation or eye 13 for convenience in mounting the 65 hanger upon a nail or other suitable support.

A slot 14 extends longitudinally of the plate 10 spaced from the lower straight edge or base 15 thereof with terminal extension slots 16 forming acute angles with the slot 70 14 and substantially parallel with the aforementioned edges 11 of the hanger.

The lower portions of the plate 10 are readily sprung laterally in opposite directions for the insertion of a suitable portion 75 of a garment such as 17, through the slot 14 and upon releasing the device the same returns to its normal position with the garment clamped therein as illustrated in Fig.

1. A curved notch 18 may be centrally provided at the inner side of the slot 14 adapted 80 for receiving the finger of the operator for propelling the lower strip or edge portion 19 of the plate from the partially severed or adjacent tongue portion 20 thereof. The inner ends of the extension slot 16 are pro-

vided with circular enlargements 21, while the connecting points between the opposite ends of the slot 14 and its extensions 16 are rounded and enlarged as at 22. A pair of 85 trousers or a skirt is readily inserted for suspension through the slot 14 and the enlargements 21 and 22 may be adapted for receiving the buttons upon a garment for partially suspending the garment and holding 90 it in position upon the hanger while coats, jackets and the like are readily wrapped around the plate 10 and suspended from the sides 11 thereof.

The moth and vermin proof feature of the 100 hanger is especially noted and consists in providing the plate 10 formed of opposite layers or strips 23 of suitable material, such as paper board or wood and having an intermediate layer or strip 24 therebetween composed of an insecticide or moth and vermin-proof material, such as cedar, creosote or formaldehyde treated substances. The moth

and vermin-proof layer 24 is in a position to engage at its upper edges 11 all articles mounted over the plate 10, while said intermediate layer also directly engages articles positioned through the slot 14.

It is broadly claimed for the device that the moth and vermin-proof members contact the garments when the hanger is in use and forms a germicide means readily packed 10 away with garments during transportation and all of which is advantageous over the known forms of garment hangers. The plate 10 also affords an extended surface 15 upon which advertising may be readily displayed, which taken with the manner of inserting and locking a garment in the slot 14 makes up a most useful article of manufacture at exceedingly low cost.

Suitable notches 25 are also provided below the slot 14 to receive the buttons of the garment.

While the form of the invention herein set forth and described is believed to be the preferable embodiment thereof it is nevertheless understood that minor changes may be made therein without departing from the spirit and scope of the invention as claimed.

What I claim as new is:—

1. An article of manufacture comprising 30 a plate of sheet material substantially triangular in form having a marginal slot provided with angular terminal extensions providing a tongue portion adapted for holding engagement with a garment when positioned through said slot.

2. An article of manufacture comprising a plate of sheet material substantially triangular in form having a marginal slot provided with angular terminal extensions 40 providing a tongue portion adapted for holding

engagement with a garment when positioned through said slot, the tongue having a substantially central finger receiving notch opening into said slot, a central extension upon said plate having an eye therein, the edge 45 portions of the plate and opposite sides of the neck being inclined adapted for the supporting reception of a garment thereover.

3. A garment hanger comprising a substantially triangular plate of laminated material having an intermediate layer of moth and vermin-proof substance, the said plate having angular slots formed therein providing a resilient locking tongue for articles mounted through the said slots whereby said 55 layer is adapted for engaging the suspended article.

4. A moth and vermin-proof hanger for garments consisting of a substantially triangular plate having opposite outer layers 60 and an intermediate moth and vermin-proof layer whereby garments positioned thereover engage the exposed edge portions of the vermin-proof layer, the said plate having a longitudinal slot spaced from its lower 65 edge terminating in angular slots substantially parallel with the upper edges of the device adapted for forming a resilient tongue having locking engagement with the garment positioned through said slot when 70 the device is in use.

5. A hanger for garments consisting of a substantially triangular plate formed of layers, one of which is a moth and vermin-proof layer, whereby garments positioned upon the 75 hanger contact the exposed edge portion of the moth and vermin-proof layer.

In testimony whereof I affix my signature.

GEORGE W. GRANT.
